(57) CLAIM

The ornamental design for an integrated illumination apparel, as shown and described.

DESCRIPTION

FIG. 1 is a front view of an integrated illumination apparel showing my new design;

FIG. 2 is a rear view thereof;

FIG. 3 is a left side view thereof; and,

FIG. 4 is a right side view thereof.

The broken lines showing throughout the figures are included for the purpose of showing environmental structure and form no part of the claimed design.

1 Claim, 3 Drawing Sheets

FIG. 1

FIG. 3
